UNITED STATES PATENT OFFICE.

WILLIAM SMITH, OF CLARINDA, IOWA.

ROTARY ENGINE.

SPECIFICATION forming part of Letters Patent No. 536,160, dated March 19, 1895.

Application filed May 8, 1894. Serial No. 510,527. (No model.)

To all whom it may concern:

Be it known that I, WILLIAM SMITH, of Clarinda, in the county of Page and State of Iowa, have invented certain new and useful Improvements in Rotary Engines; and I do hereby declare that the following is a full, clear, and exact description thereof, reference being had to the accompanying drawings, and to the letters of reference marked thereon, which 10 form a part of this specification.

This invention relates to improvements in rotary engines of a generally similar type to those set forth in my previous patents, Nos. 517,985 and 517,986, dated April 10, 1893, and 15 has for its object to provide an engine of greater efficiency and superior economy in steam consumption.

To this end the invention consists in the matter hereinafter set forth and particularly 20 pointed out in the appended claims.

A principal feature of my invention consists in revolvably mounting the smooth wheel which acts as a rotary piston within the cylinder, upon a crank formed on the driving 25 shaft, so that under the pressure of the steam said wheel will roll around the inner surface of the cylinder and act upon the crank in the same manner as the piston of an ordinary reciprocating engine.

30 A further feature of my improvement consists in operating the sliding abutment which rests constantly upon the rotary piston and separates the steam space of the cylinder from the exhaust space thereof, by means of radial 35 links pivotally connecting said abutment with the crank pin upon which the revoluble piston is mounted.

A third feature of my invention consists in providing a cut off valve operated by the sliding abutment plate by means of which the quantity of steam admitted at each revolution of the engine may be varied as desired without regard to the proportions of the cylinder and piston.

45 In the accompanying drawings: Figure 1 is a sectional elevation of a rotary engine constructed in accordance with my invention. Fig. 2 is a partial section taken on line 2—2 of Fig. 1. Fig. 3 is a sectional elevation taken 50 on line 3—3 of Fig. 1.

A designates the engine cylinder which is

mounted upon a suitable base A', and is in this instance cast integral therewith.

B is the main driving shaft of the engine and extends into the cylinder A through central stuffing boxes a in the heads A² thereof, said shaft being revolvably mounted within suitable bearings a' supported upon standards A³ which are bolted to the base A'. Within the cylinder A the shaft B is formed 60 with a crank B' upon the crank pin B² of which a smooth cylindric wheel C, which forms the rotary piston, is revolvably mounted so as to bring its periphery in rolling contact with the inner cylindric surface of said cylinder A. For the purpose of enabling the contact between the cylindric surfaces of the cylinder A and wheel C to be adjusted as desired and to provide for the taking up of any wear which may occur between them, the end 70 portions b of the crank pin B² are made to revolvably engage suitable apertures in the arms b' of the crank and are adjustably secured therein by means of set screws b², the central portion b³ of the crank pin, upon which 75 the smooth wheel C is mounted, being at the same time formed eccentric to the end portions b which engage the crank arms b'. With this construction it will be obvious that by revolvably adjusting the crank pin in the crank 80 arms b' the wheel C may be carried toward or away from the inner surface of the cylinder as may be desired.

D designates a sliding abutment plate or plunger projecting into the cylinder from a steam chest A⁴ provided on the top thereof, said plate being closely fitted to reciprocate within a suitable vertical recess a² provided in said steam chest. Said plate, in my improved construction, is maintained in constant 85 contact with the periphery of the piston wheel C by means of radial links E, the inner ends of which are sleeved upon the central portion b³ of the crank pin B² on either side of the hub c of the wheel, and between said hub and 90 the crank arms b'. Said arms b' extend upwardly on either side of the central web c' of the wheel and have their upper ends e' bent outwardly to pivotally engage lateral arms or lugs d provided on the sides of the block D 100 and projecting inward past the edges of the rim c² of the wheel. Said arms d are in this

instance formed by the lower ends of separate strips D' which are secured to the side edges of the plate D by suitable screws d² or otherwise, and which reciprocate within vertical slots a³ provided in the inner faces of the heads A' of the cylinder and extending downward a sufficient distance to permit the required downward movement of the plate D. The lower end of the plate D is further shown 10 as provided with an inner block D which fits within a recess d³ in the block D and is maintained under yielding pressure by springs d⁴ in the upper portion of the recess D². Said inner block D², which is similar to that set forth in my previous patent, No. 517,986, dated April 10, 1893, obviously acts as a packing to compensate for any wear which may occur between the lower face of the block D and the periphery of the wheel C and to maintain a practically steam tight joint between the plate and wheel at all times.

Suitable steam and exhaust ports a⁴, preferably made exactly similar in shape, are provided on either side of the abutment plate D. 25 At their outer ends said ports are adapted to receive pipes F which, as herein shown, are provided with three way valves F' which serve to connect each of the pipes F with both steam and exhaust pipes G and H respectively. 30 The valves F' are designed to be simultaneously operated by levers f which are pivotally connected by a link f', in such manner that when the handle of one valve is moved so as to throw the adjacent pipe F in communication with the steam pipe G the handle of the other valve will be so moved as to throw the other pipe F in communication with the exhaust pipe H, and vice versa. Obviously with this construction the engine is adapted 40 to rotate in either direction and may be reversed at any time by shifting the handles f. The reversing mechanism described forms no part of my present invention and has been fully set forth in connection with my previous patent, No. 517,985, dated April 10, 1893, hereinbefore referred to.

As a further and distinct improvement and for the purpose of enabling the admission of steam to be cut off at any part stroke instead 50 of being admitted throughout substantially the entire revolution of the piston, as in my previous engines, I have in this instance shown a cylindrical valve chest A⁵ mounted upon the top of the steam chest A⁴ and have 55 provided within said chest a piston valve I. The latter is connected with the abutment plate D to reciprocate therewith by a valve rod I' engaging said plate and valve at its opposite end and passing through a stuffing box 60 a⁵ in the top a⁶ of the steam chest by means of which leakage between the valve and steam chests is prevented. The steam pipes G, as herein shown, open into the valve chest A⁴ at diametrically opposite points a⁷ somewhat 65 above the center thereof and are supplied with steam through said valve chest from a supply pipe J opening into the top thereof,

except at such times as the valve I by its upward movement acts to cover said openings a⁷ and thus cut off the steam supply to the pipes 70 G. The parts are so proportioned that the downward movement of the valve I begins to uncover the openings a⁷ as soon as the plunger I' begins to descend after the piston C has passed its uppermost position. Steam will 75 therefore begin to flow at this point through that one of the pipes G between which and the cylinder communication has been established through the three way valves F', and will continue to flow until the valve I has 80 reached its lowermost position and risen again far enough to close the openings a⁷. By such closing of the openings a⁷ the steam will obviously be cut off and will cease to flow until 85 said openings are again uncovered by the downward movement of the valve piston. Such point of cut off is in this instance provided at about three fourths of the stroke. Obviously, however, although the three 90 fourths cut off arranged for in this instance is deemed desirable for many purposes, the parts may be readily so proportioned as to provide an earlier or a later cut off if so desired. It will further be obvious that in cases where it is desired to have the engine rotate in one direction only, one of the steam pipes G and the 95 opposite exhaust pipe H together with the three way valve connections shown may be entirely dispensed with, the remaining steam pipe G being left in communication with the port a⁴ on one side of the abutment and the remaining exhaust pipe with the port a⁴ on the other side of the said abutment.

In the operation of the engine thus described the steam admitted at one side of the 105 abutment plate D will obviously exert a direct pressure on the periphery of the wheel C which will at once be transmitted to the crank pin and tend to rotate the crank shaft in substantially the same manner as in a reciprocating engine, with the obvious additional advantage that such rotary impulse on the crank pin, instead of being interrupted twice in each revolution by dead center points, is interrupted at only one point which will occur as 115 the piston wheel C reaches its uppermost position. Furthermore, it will be obvious that the rolling contact between the inner surface of the cylinder and the periphery of the piston wheel C will offer almost no resistance to 120 the rotation of the engine, so that the engine is not only very effective in its application of power, but involves the loss of very little of the power generated, in the friction of moving parts. As soon as the steam is cut off by 125 the piston valve I expansion occurs in the cylinder A in the same manner as in a reciprocating engine, and as hereinbefore stated such expansion may be carried on to any desired degree by the proper arrangement of the cut 130 off gear.

I claim as my invention—

1. In a rotary engine the combination with the steam cylinder of a concentrically mount-

ed driving shaft provided with a crank within the cylinder, a smooth cylindric wheel revolvably mounted on said crank with its periphery in rolling contact with the interior of the cylinder, a reciprocatory abutment plate means for positively maintaining said plate constantly in contact with the surface of said wheel, and steam and exhaust ports on opposite sides of said plate, substantially as described.

2. In a rotary engine the combination with the steam cylinder of a concentric driving shaft provided with a crank within the cylinder, the pin of said crank being made with eccentric end portions adjustably engaging apertures in the crank arms, a smooth cylindric wheel revolvably mounted on said crank pin with its periphery adjustably engaging the inner surface of the cylinder and in rolling contact therewith, a reciprocatory abutment plate constantly engaging the surface of said wheel, and inlet and exhaust ports on opposites of said plate, substantially as described.

25 3. In a rotary engine the combination with the steam cylinder of a concentric driving shaft provided with a crank within the cylinder, a smooth cylindric wheel revolvably mounted on the crank pin with its periphery in rolling contact with the inner surface of the cylinder, a reciprocatory abutment plate, and radial arms pivotally connecting the abut-

ment plate with the crank pin to maintain the plate in constant contact with the surface of the wheel, substantially as described.

4. In a rotary engine the combination with the steam cylinder of a concentric shaft provided with a crank within the cylinder, a smooth cylindric wheel revolvably mounted on said crank with its periphery in rolling contact with the inner surface of the cylinder, a reciprocatory abutment plate constantly engaging the surface of said wheel, a steam chest within which said abutment plate reciprocates, steam and exhaust ports on opposite sides of said abutment plate, a valve chest mounted on said steam chest and provided with a valve connected with the abutment plate to reciprocate therewith, a steam pipe leading from said valve chest to the steam port and adapted to be closed on its upper end by said valve piston during a portion of the stroke thereof and a steam supply pipe opening into said valve chest and communicating with said steam pipe when the latter is uncovered by the valve piston, substantially as described.

In testimony that I claim the foregoing as my invention I affix my signature in presence of two witnesses.

WILLIAM SMITH.
